UNITED STATES PATENT OFFICE.

AUGUSTUS C. GRUHLKE, OF WATERLOO, INDIANA.

CIGAR-LIGHTER.

No. 879,632.

Specification of Letters Patent.

Patented Feb. 18, 1908.

Application filed June 13, 1906. Serial No. 321,565.

To all whom it may concern:

Be it known that I, AUGUSTUS C. GRUHLKE, a citizen of the United States, and a resident of Waterloo, in the county of Dekalb and 5 State of Indiana, have invented a certain new and useful Improvement in Cigar-Lighters, of which the following is a full, clear, and exact description, reference being had to the accompanying drawing, which forms a part 10 of my specification.

My invention relates to that class of cigar lighters which employ a volatile fluid, and are electrically ignited when it is desired to use them; it being designed for use at cigar 15 stands and the like, and which will become automatically extinguished, as will be more fully hereinafter set forth and described.

In the drawings:—Figure 1 is a side elevation of my improved cigar lighter, showing 20 the lighter in its normal state, Fig. 2 is a side elevation of the same, showing the lighter in the condition it assumes after the electrodes have been brought into, and broken contact, and a spark produced, whereby the wick is 25 ignited, Fig. 3 is a longitudinal view taken through the lighter, a little to the side of the overhead electrode.

Like letters of reference indicate identical parts in the various figures.
30 A is the base or receptacle for the fluid, as for instance gasoline, and into which the wick *a* is inserted. This wick *a* is preferably made of asbestos fiber. The wick *a* passes up from the receptacle A, through the wick 35 tube B, as shown in Fig. 3, extending but slightly above the wick tube, as is customary in lighters of this class, so as to permit of ignition of the vapor formed at this point. The wick tube B is inclosed in a tube or casing 40 C, which is provided at its upper end with the beveled face *c*, and which extends slightly above the wick tube B, so as to form a small chamber at this point for the reception of vapor or gas thrown off by the saturated wick *a*. The casing C extends above the wick tube B, as above set forth, and provides a chamber above the wick tube B, sufficiently large to permit the spreading out of the wick *a*. This permits of the accumulation 45 of vapor or gas at this point which will be sure to ignite upon the making and breaking of contact of the two electrodes.

The tube or casing C is provided on its one side with an extension or slide-way D, as 5 seen in Figs. 2 and 3, about which is fitted the tube or slide E. Pivotal secured to the

tube or slide E are the arms F, of which there are preferably two, one on each side, having their connection with the tube or slide E at the pivotal point *d*. These arms F are preferably secured together at their outward end, and provided with a thumb-rest *e*. Secured to the tube or casing C, in any suitable manner, as for instance by a screw *f*, is a flat spring *g* which at its upper end takes between 60 the arms F and bears against the point of connection of the arms F at the thumb-rest *e*, as shown in Figs. 1 and 3. This flat spring *g* may either be secured to the arms F by the same bolt or screw by which the thumb-rest 65 *e* is secured thereto, or the spring may be slightly bowed at this point, so as to give it a sliding contact with the arms F at their point of connection with the thumb-rest *e*, as shown in the drawings. The tube or slide E 70 is also provided with the extinguisher G, which is constructed to conform with the beveled edge of the casing or tube C, and snugly fit over the same. The extinguisher or cap G is also provided with an angular extension or standard H, which supports the counter-balanced electrode *h*. The counter-balanced electrode *h* is pivotally secured to the extension H, as seen at *i*; the contact point of the electrode *h* being in the nature of 75 a small coil-spring extending down and below the top of the tube or casing C, as clearly 80 illustrated in the drawings.

The upper portion of the tube or casing C is provided with a metal plate or electrode *j* 85 which is secured thereto, but insulated therefrom by the block of insulating material *k*.

l, *m*, are wires leading from a battery placed at any convenient point: the wires *l*, *m*, are insulated from each other, and pass 90 through the small sleeve *n* which is secured to the tube or casing C. The one wire *l* passes up between the tube or casing C, and the wick tube B to the insulated metal plate or electrode *j*, while the other wire *m*, has 95 electrical contact with the casing C immediately beneath the sleeve *n*. It will thus be seen that by reason of the fact that the casing or tube C as well as the extension D formed thereon, and the tube or slide E contacting 100 with the extension D, and the extinguisher G, on which is secured the electrode *h*, are made of metal, and the one wire having contact with the metal plate *j*, but insulated from the tube C, that when the contact point 105 of the electrode *h* comes into contact with the plate *j*, the circuit will be completed; and im-

mediately upon the tube or slide E being slid outwardly and further away from the tube C, the circuit will be broken and a spark produced at the contact points, which will ignite

5. the gas or vapor accumulated in the chamber c, which chamber will have at that time become uncovered by the extinguisher or cap G being slid away.

Secured to the tube C at a point preferably 10 above the arms F, is a cigar-tip receiver p. This cigar-tip receiver or guide is preferably constructed of a strip of metal, having the opening p' therethrough at its outward end. Secured to the extinguisher G at a point in the 15 same horizontal plane with the cigar-tip receiver, is a knife r, which in its normal position lies immediately adjacent the receiver p. It will be seen that by inserting the tip of the cigar in the opening p' of the receiver p, and 20 pressing on the thumb-rest, thus sliding the extinguisher G away from the tip of the tube C, the knife r will also slide with it, and the tip of the cigar protruding through the opening p' will be sheared or cut off. The knife r 25 is preferably constructed with the beveled edge, so as to produce a shearing cut.

s is a grasp secured to the side of the tube C opposite to the thumb-rest e. The grasp is 30 really not essential, as far as the operation of the lighter is concerned, but insures the proper grasping of the lighter, and prevents the hand of the user or operator from coming into contact with the tube or slide E, and interfering with its easy operation.

35. It will be seen that the electrode h will immediately be returned to its normal position, and be ready for the next operation, by reason of the fact that it is counter-balanced, as shown; and at the same time, it is very simple 40 in construction and durable, with little possibility of becoming out of order. The style of contact-point, consisting of the coiled wire h', that I am enabled to use in this construction, is one that will give far better results with one-half the current of electricity 45 that is necessary for the style of electrodes heretofore used in devices of this character, which consisted of small metallic plates or points, pivotally secured and held in normal 50 position by springs.

The operation of the lighter is very simple, and the extinguishing of the flame is always insured by reason of the spring I am enabled 55 to employ in this construction, which, immediately upon the release of the lighter, forces the extinguisher on to the tube-tip, and extinguishes the flame, and at the same time fits closely on the tube-tip and prevents the evaporation of the vapor or gas formed at 60 this point.

65. With a gas chamber formed as at c, I am enabled to spread out the wick a to produce a sufficient amount of vapor or gas in the chamber, and yet, at the same time, prevent its being "batted down" by the extinguisher, as

is the case in the construction of the lighters heretofore used. Furthermore, the vapor or gas is retained in the chamber at the point desired.

I have described and illustrated in the drawings, what I consider a convenient and, at the same time, simple form of construction of my invention, which may be modified in any suitable manner, as for instance, instead of employing the tube E, a simple slide may 70 be made to ride on the extension D; or, guides or slide-ways might be made on the sides of the tube or casing C, between which the arms F may take, and in that event the extension D, as well as the tube E might be 75 done away with; the extinguisher G, together with the knife attached thereto, simply being secured to arms F. Furthermore, the tube or casing C might be given a thick 80 wall, so as to have its internal diameter just 85 sufficiently large to receive the wick a, but have its orifice or top portion flared out slightly, if desired, to produce a small gas chamber. In that event, instead of having the wire pass up on the inside of the casing C 90 (as in this case no wick tube would be necessary), the wire might be passed up on the outside, or an opening be made in the wall of the casing C lengthwise thereof, through 95 which the wire might be passed; and other slight modifications may be made without departing from the spirit of my invention: but

What I claim as my invention and wish to secure by Letters Patent is:—

1. An electrically ignited fluid burning lighter, comprising a fluid receptacle, a tube or casing leading therefrom for the reception of the wick, an electrode secured adjacent to the tip of said tube or casing, an extinguisher 105 normally held over said tube or casing, and adapted to move substantially at right angles to said tube, said extinguisher being provided with an opposite electrode to be brought into contact with the electrode on the tube tip when the extinguisher is moved, and means connected with the extinguisher whereby the latter is moved, and so related to the tube or casing as to be directed in its movements thereby.

2. An electrically ignited fluid burning lighter, comprising a fluid receptacle, a tube or casing leading therefrom for the reception of the wick, an electrode secured adjacent to the tube or casing tip, an extinguisher adapted to move substantially at right angles to said tube and provided with an opposite electrode, means connected with the extinguisher whereby the latter may be moved away from the tube or casing tip, said means so related to the tube or casing as to be directed in its movement thereby, and mechanism for returning said means and the extinguisher to their normal position.

3. An electrically ignited, fluid burning

lighter, comprising a fluid receptacle, a tube or casing leading therefrom for the reception of the wick, an electrode secured adjacent to the tube or casing tip, an extinguisher adapted to move to and from said tube, and provided with an opposite electrode, arms extending on opposite sides of said tube or casing and connected with the extinguisher, whereby the latter is moved in a defined path 10 substantially at right angles to the tube or casing tip.

4. An electrically ignited fluid burning lighter, comprising a fluid receptacle, a tube or casing leading therefrom for the reception 15 of the wick, an electrode secured adjacent to the tip of said tube or casing, an extinguisher normally held over said tube or casing and provided with an opposite electrode, arms extending on opposite sides of the tube or 20 casing and connected with the extinguisher whereby the latter is moved in a defined path substantially at right angles to the tube or casing tip, and means acting on said arms whereby the latter, with the extinguisher, 25 are returned to their normal positions.

5. An electrically ignited fluid burning lighter, comprising a fluid receptacle, a tube or casing leading therefrom for the reception of the wick, an electrode secured adjacent 30 to the tube or casing tip, an extinguisher normally held over said tube or casing tip, said extinguisher being provided with an opposite electrode, and means connected with the extinguisher and having sliding contact 35 with the tube or casing whereby the direction of its movement and the extinguisher is controlled.

6. An electrically ignited fluid burning lighter, comprising a fluid receptacle, a tube 40 or casing leading therefrom for the reception of the wick, an electrode secured adjacent to the tube or casing tip, an extinguisher normally held over said tube or casing tip, said extinguisher being provided with an 45 opposite electrode, means connected with the extinguisher and having sliding contact with the tube or casing whereby the direction of its movement and the extinguisher is controlled, and mechanism intermediate of the 50 tube or casing and said means whereby the latter, with the extinguisher, are returned to their normal positions.

7. An electrically igniting fluid burning lighter, comprising a fluid receptacle, a tube 55 or casing leading therefrom for the reception of the wick, an electrode secured adjacent to the tip of said tube or casing, an extin-

guisher normally held over said tube or casing tip and provided with an opposite electrode, a guide-way secured to said tube or 60 casing, a slide connected with the extinguisher and adapted to take on the guide-way, and means for moving said slide with the extinguisher to and from the tube or casing tip. 65

8. An electrically igniting fluid burning lighter, comprising a fluid receptacle, a tube or casing leading therefrom for the reception of the wick, an electrode secured adjacent to the tip of said tube or casing, an extinguisher 70 normally held over said tube or casing tip and provided with an opposite electrode, a guide-way secured to said tube or casing, a slide connected with the extinguisher and adapted to take on the guide-way, means for moving said slide with the extinguisher to and from the tube or casing tip, and mechanism intermediate of said means and the tube or casing for returning the slide and the extinguisher to their normal positions. 75

9. An electrically ignited fluid burning lighter, comprising a fluid receptacle, a tube or casing leading therefrom for the reception of the wick, an electrode secured adjacent to the tip of said tube or casing, an extinguisher 80 normally held over said tube or casing tip and adapted to move substantially at right angles to said tube, a counter-balanced electrode pivotally secured to the extinguisher, and means connected with the extinguisher whereby the latter may be moved, and so related to the tube or casing as to direct the movement of the extinguisher. 95

10. In an electrically ignited fluid burning lighter, the fluid receptacle, a tube leading therefrom for the reception of the wick, an electrode secured adjacent to said tube tip, an extension secured to the tube and at substantially right angles thereto, an extinguisher adapted to slide on said extension and to take over the tube tip, arms secured to said extinguisher whereby the latter may be made to slide along said extension, a counter-balanced opposite electrode pivotally secured to the extinguisher, and means 100 acting on said arm whereby the latter and the extinguisher are returned to their normal positions. 105
